UNITED STATES PATENT OFFICE

BENJAMIN F. JOLINE, OF TOTTENVILLE, NEW YORK, ASSIGNOR TO AMERICAN EVER READY COMPANY, A CORPORATION OF NEW YORK.

PRINTING MECHANISM.

1,080,913.

Specification of Letters Patent.

Patented Dec. 9, 1913.

Application filed May 8, 1910. Serial No. 559,077.

To all whom it may concern:

Be it known that I, BENJAMIN F. JOLINE, a citizen of the United States, residing at Tottenville, in the county of Richmond and State of New York, have invented certain new and useful Improvements in Printing Mechanism; and I do declare the following to be a full, true, and exact description of the said invention, such as will enable others skilled in the art to which it appertains to make and use the same.

This invention relates to printing devices in which a relatively small number of words, letters and figures, or any of them, are mounted on a movable support or supports, in order to bring any of them to the printing point, either singly or in predetermined groups, as desired, and in which after the required number of impressions are taken, the supports are returned to normal position preparatory to bringing a new set of printing characters to the printing point.

One of the objects of this invention is to provide a simple mechanism by which the types on the supports can be readily grouped by the operator in any desired manner.

Another object of my invention is to provide a simplified key-board by which the operator can select the types to be printed before the actual printing operation takes place, so that if any mistake is made by the operator in pressing the keys, it may be corrected without spoiling an impression.

Another object of my invention is to provide mechanism by which the determining keys are restored automatically to initial position after each printing operation, so that the operator, by setting the keys a second time, can determine a new group of characters for the second printing operation.

Another object of my invention is the provision of means by which after the printing characters are properly assembled, any number of impressions may be struck off by the operator without disturbing the group of characters.

Another object of my invention is the provision of inking mechanism which will enable the various type supports to be moved to varying positions without interfering with the operation of each other.

Another object of my invention is the provision of a new and improved form of key mechanism.

Another object of my invention is to pro-

vide an operating means movable between two defined limits and yieldingly connected to a support for type, so that the movement of the support may be stopped without in any way affecting the movement of the operating device.

Another object of my invention is the provision of a suitable support for the object to be printed whereby, after the object has been located on the support, the operator may cause the type to be impressed at a selected place on the object.

With these and other objects in view, the invention consists of certain novel features of construction, combination and arrangement of parts, as will be more fully described and pointed out in the appended claims.

For purposes of illustration, the invention is shown as adapted to a mechanism for printing checks with the amounts for which they are drawn, but the mechanism is useful generally in any printing device in which it is desirable to assemble letters and figures, or either of them, for printing purposes, such as machines for marking linen, railroad tickets or similar objects, numbering machines or machines for writing in items and figures in any system of accounting, such as is sometimes used in filling in customers' orders in restaurants or the like.

In the drawings, Figure 1 is a front elevation of the invention as adapted to a check writer. Fig. 2 a side elevation thereof of looking from the left of Fig. 1. Fig. 3 is a plan of a portion of Fig. 1. Fig. 4 is a section of Fig. 1, looking from the left thereof and taken generally on the line 4-4. Fig. 5 is the same as Fig. 4 with the mechanism in another position. Fig. 6 is a partial section of Fig. 4, taken on the line 6-6. Figs. 7 and 8 are views of a detail construction shown in two different positions, and Fig. 9 is a side elevation of Fig. 8. Fig. 10 is one view of the inking mechanism and Figs. 11 and 12 are side views thereof. Fig. 13 is a composite view of a detail of the key mechanism, showing the front and side elevations and plan thereof.

Corresponding parts are referred to both in the drawings and the following description by similar reference characters.

In the accompanying drawings 21 is a shaft journaled at its ends in the body casting 22.

23 is a handle attached to shaft 21 by means of the arms 24—24.

25, 26, 27, 28, 29, and 30, are typewheels mounted on the shaft 21.

5 31 represents a spring, which is attached at one end to the typewheel 25 by means of a pin such as 84 in the web of the typewheel, and at the other end to the shaft 21 through a collar or spacing member 34, this 10 collar being fastened to the shaft 21.

15 32 and 33 represent springs similar to 31, being attached respectively to the typewheels 26 and 27 and the collars 35 and 36. Each of the typewheels 28, 29 and 30 is provided with a similar spring.

Attached to either end of the shaft 21, inside of the casing 22 are arms 37—38, which are slotted at their outer ends, as at 39, and in these slots and slidably supported 20 thereby is a bar 40 having one side slightly beveled, as at 41. Pivoted on screws 45 at either end of this bar 40 are cam plates 42, which cam plates have cam slots 43 therein, and in the said slots 43 are pins 44, fastened to the arms 37—38.

25 In the casing 22 are slidably mounted pins 46, 47, 48, and 49, these pins normally projecting inwardly through the casing 22.

30 Each of the typewheels 25 to 30 have types thereon, as at 50, these types being spaced from each other on the separate wheels, as shown in the drawings. These types may be single characters, as letters or figures, or may be words. Each typewheel 35 also has a projection thereon, as at 51 and 52. In the drawings is shown a keyboard device, to be more specifically described hereafter, in which keys, such as 54 are slidably mounted so as to be moved toward and 40 away from the shaft 21, and normally held in the position indicated by the key 55.

45 The mechanism so far described enables the operator, by pushing inward any of the keys 54 and turning the handle 23 from the position shown in Fig. 4 to the position shown in Fig. 5, to bring any predetermined type on the typewheels to the printing point, and to return such typewheels to their normal position, as shown in Fig. 4, by moving 50 the handle 23, from the position shown in Fig. 5 to the position shown in Fig. 4.

Assuming that a key such as 54 is pushed inward by the operator, the motion of the handle 23 from the position shown in Fig. 4 to 55 that shown in Fig. 5 carries the typewheels around with it through the yielding connection of the springs, such as 31, with the shaft 21, until the typewheels are stopped from further motion in this direction by 60 such stops, as 54, which have been pushed inward. By reason of this yielding connection, however, the stopping of one type wheel does not prevent the further progress of the shaft 21 nor of any of the other typewheels connected thereto. The cam bar 40

in the motion of the handle from the position in Fig. 4 to that in Fig. 5, is carried at the lower end of the slots 39 in the arms 37—38, but as the handle 23 approaches the position shown in Fig. 5, the cam plates 42 70 strike respectively against the pins 46—47, and are swung on their pivots 45. Since the pins 44 are fixed in the arms 37—38, and engage the cam slots 43, such a motion of the cam plates 42 moves the bar 40 outward toward the ends of the slots 39 in the arms 37—38, as is illustrated in Figs. 8 and 9. Now on the return motion of the handle 23 from the position shown in Fig. 5 to that shown in Fig. 4, the cam bar strikes against 80 such keys as 54 as have been pushed inward and moves them outward or to the normal position, as shown at 55. The cam bar 40, whether in its inward or outward position, moves in the same circular path as the projections 51—52 and strikes such projections on the return motion of the handle from the position shown in Fig. 5 to that shown in Fig. 4, thus moving all of the type wheels to normal or inoperative position, as shown 85 in Fig. 4. It should be understood that this mechanism is so proportioned and designed that the projections 51—52 on the type wheels do not strike the stops 54—55 unless these stops are pushed inward from the position shown at 55 and that the cam bar 40 does not strike the stops 54—55 unless they are pushed inward, and then only when the cam bar is moved to the outer ends of its slots 39, as shown in Fig. 8.

90 The pins 46—47 are attached to the ends of bars 56—57 respectively, and these bars are slidably mounted in the casing 22. At the inner end of the bars 56—57 are pins 58—59, which engage with cam slots in rotatably mounted member 60. On the turning 95 of this member 60 clockwise from the position shown in Fig. 1 through about 90 degrees, the cam bars 56—57, by reason of the engagement of the pins 58—59 thereof with the cam slots in the member 60 move the pins 46—47 outward, so that the ends thereof are no longer in the path of the cam plates 42. When this is done, if the handle 23 is moved 100 from the position shown in Fig. 4 to that shown in Fig. 5, the cam plates 42 are not moved and the bar 40 remains at the inner end of the slot 39, and therefore, this bar is not positioned on the return stroke of the handle to strike against such of the keys 54 105 as may have been moved inward, and the relation of such keys to the key-board is not disturbed. With this arrangement any number of impressions may be taken from the same group of types without a re-setting 110 of the keys after each impression, as would be necessary if the mechanism for moving the pins 46 and 47 were not provided. It will be understood that the cam plates 42 115 have frictional engagement with the pivots 120

100

130

45, and with the arms 37 and 38 to retain them either in the position of Fig. 7, or that of Fig. 8, unless they contact with the pins 46—47 or 48—49.

5 A platen mechanism for moving the object on which the impression is to be made toward the type wheels is provided at 61. This platen is a bar extending across the machine and slidably supported on the casing 22, and provided with a rubber pad, if desired. The platen, may, if desired, be provided with metal cutting or perforating projections, in which case the types would be provided with coöperating projections, this 10 form of platen and type being common in the art. The platen is moved upward and downward by a toggle mechanism at each end thereof, as shown in the drawings, and this toggle mechanism is operated by the motion 15 of the handle 24, by means of a lever 62 attached to the shaft 21 and carrying a pin thereon, which when the handle 23 approaches the position shown in Fig. 5, strikes against an arm 63 and moves the 20 toggle mechanism from the position shown in Fig. 4 to the position shown in Fig. 5, in order to move the platen 61 upwardly from the position shown in Fig. 4 to that shown in Fig. 5, as will be readily understood by those 25 familiar with the art. On the return motion 30 of the handle 23 from the position shown in Fig. 5 to that shown in Fig. 4, the arm 62 moves its pin out of contact with the arm 63 and the platen falls to the position shown in 35 Fig. 4.

The key board mechanism consists of curved plates 64—65 attached to the outside of the casing 22. The plate 64 is of considerable thickness and has circular apertures corresponding to similar apertures in the casing 22, to provide a sliding bearing 40 for the keys 54. One of these keys is shown much enlarged in Fig. 13, and as shown, is provided with a spring seated ball 45 66. The plate 65 is relatively thin and has squared apertures in it, corresponding to the openings in the plates 64, and the casing 22, when the plates 64 and 65 are assembled on the casing 22. The centers of the squared 50 apertures in the plate 65 are first made to correspond with the centers of the circular openings in 64 and 22 when the keys are inserted. The plate 65 is then slid around 55 slightly in relation to the plate 64, so as to bring one edge of the squared apertures in 65 into the slot 67 in the keys. After this is done, each key has an inner and outer support in the plate 64 and the casing 22, and is limited in its sliding movement by the edges 60 of the squared apertures in the plate 65, the ball 66 contacting either with the upper side of plate 65, as is shown in Fig. 13, or with the lower side thereof. At the same time, by reason of the contact between the rear of 65 the slot 67 with the squared aperture in the

plate 65, the keys are prevented from rotation on their own axes. It will be understood by an inspection of Fig. 13, that pressure on the top of the key will move it downward, the spring seated ball 66 being pressed inward until it is below the plate 65, when its spring pushes it outward to engage with the lower side of the plate 65, to hold the key in its new position. Each of the keys is preferably beveled on one side, as shown at 68, to coöperate with the corresponding bevel 41 on the cam bar 40.

70 The keys of the keyboard are arranged in groups around each typewheel, each group controlling a separate wheel, and each key of the group determining the stopping point of the wheel to position at the printing point, a type represented by that key.

75 The inking mechanism consists of an inking roller 69, and a supply roller 70. These rollers are removably mounted in a swinging frame having arms 71 and 72, and this frame is spring pressed by the springs 73, to hold the inking roller 69 against the type wheels 25 to 30. The inking roller 69 is so positioned in relation to the printing line which is directly above the platen 61, that when any typewheel is moved so that a type on its periphery is at this printing line, the inking roller 69 will fall in a space between the 80 types on that wheel, as shown in Fig. 5. It will be understood that in the mechanism illustrated in the drawings, the typewheels may, and usually do, arrive at their respective printing positions at different times during the movement of the handle 23. The rotation of the wheels which have not yet arrived at their printing positions, will have a tendency to rotate the roller 69. If the inking roller were in contact with the type 85 of the typewheel which had been stopped, this roller would be restrained from rotation, whereas, in the arrangement shown, the roller is not in contact with the type of a typewheel after the latter has come to rest, 90 and therefore, may be freely rotated by such typewheels as have not yet arrived at their printing positions. This arrangement enables me to use a single inking roller for a plurality of typewheels, instead of dividing 95 this roller into a number of separate sections individually rotatable for each typewheel, as has heretofore been done in similar printing devices. It will be understood that the inking rollers which I have illustrated are of 100 the well-known type, in which a cloth or other fabric surface of both the inking and supply rollers is charged with a quantity of ink sufficient for many impressions.

105 The frame with the arms 71 and 72 is 125 journaled on a shaft mounted in lugs 74—74, attached to the inner side of a portion of the casing 22, indicated at 75. This portion of the casing 75 is pivotally mounted on pins 76, so that it may be swung downward, 110

to enable the operator to supply the rollers 69—70 with a fresh supply of ink. On moving the section 75 to the position shown in Fig. 4, the inking rollers are entirely concealed and are not liable to soil the objects which are being printed.

77 is a flat plate slidably longitudinally in the casing 22 and having gage members 78 and 79 thereon. These gage members may be adjusted for various sizes of paper or other objects which are to be printed. The plate 77 has a slot 80 therein, through which the platen 61 may rise and carry an object laid on 77 upwardly against the type of the typewheels. The plate 77 is slidably supported on the rods 81—81, and has a handle 82 attached thereto, by which it may be moved longitudinally across the machine to bring the object to be printed to its proper printing position. It will be understood that the plate 77 is moved to the right (Fig. 1) as far as possible when the object to be printed is inserted and is then moved to the left to a position somewhat as shown in Fig. 1 when the impression is taken. The body member 22 is provided with a scale just above the handle 82, the latter serving as an index for the plate 77. In a device for printing checks, such as is shown in the drawings, it is desirable to enable the operator to print the first word of the amount of the check at the extreme left of the check, to prevent the "raising" of the amount. The sliding plate 77 in connection with the scale enables this to be done. The guides 78 and 79 are first adjusted so as to properly locate a check of the size to be printed. Now, if an amount beginning in "thousands" is to be printed, the handle 82 is moved to the left till the handle 82 is under that mark on the scale which shows that the left hand end of the check is under the wheel 30, which carries the "thousand" amounts. If the next check is to be printed in an amount beginning in "hundreds", the handle 82 is moved till it coincides with the "hundreds" marks on the scale, and the left hand end of the check will then be under wheel 29, which is the "hundreds" wheel. Similarly the scale enables the operator to bring the left hand end of the check under any of the printing wheels.

While I have shown for purposes of illustration, the specific device for supporting and guiding the object to be printed, indicated at 77, 78, and 79, it will be understood that many modifications of this form of support are possible, and I do not wish to limit myself to the specific form illustrated.

60 The keys 54—55 will have thereon appropriate marks to indicate the particular types which will be brought to the printing point when the key is pressed, and I have also provided a head 83, having one edge beveled, 65 and on which may be placed appropriate

marks to indicate the kind of characters controlled by a series of keys in line with the given mark, as shown in Fig. 1.

I have shown as a yielding connection between the typewheels and the shaft 21, the 70 spring 31, but I do not wish to limit myself to this specific device. Many modifications of the yielding connection between the typewheels and the shaft are possible, and such a yielding connection may be obtained simply by a frictional contact between the hubs of the typewheels and the shaft, it being understood that in such a form of yielding connection, for my purpose only enough friction is required to carry the type wheels 80 with the shaft 21 so long as the typewheels are not opposed in their movement and when such opposition occurs, the shaft is permitted to continue its motion even though one or all of the wheels have been stopped 85 in their movement.

While I have shown my type supports as circular members, my invention contemplates broadly any form of type support, and an operating mechanism therefor yieldingly connected to the type supports so as to permit the stopping of the latter at predetermined points without interfering in any way with the continuous forward motion of the former.

It should be also understood that while I have for purposes of illustration shown a plurality of typewheels, my invention is not limited to such plurality, but may be used with only one such typewheel, it being desirable to have the handle 23 move through a defined path at all times, in order to operate the platen mechanism at the end of its motion, and it is also desirable to be able to stop the typewheel at any given point, in 105 order to bring a predetermined word or figure to the printing point.

Having now described my invention, what I claim as new and desire to secure by Letters Patent is as follows:—

1. A rotatable shaft, a typewheel mounted thereon and yieldingly connected thereto, and a plurality of stops, each of which is movable into engagement with said typewheel wholly by the operator and is held 115 yieldingly either in or out of engagement with said typewheel, substantially as described.

2. A rotatable shaft, means whereby it may be oscillated, one or more typewheels 120 mounted on said shaft and yieldingly connected thereto, a plurality of stops for each typewheel, each of which is movable into engagement with said typewheel wholly by the operator and is held yieldingly either in or out of engagement with said typewheel, and means to move the said stops out of engagement with the said typewheels, substantially as described.

3. A rotatable shaft, a typewheel mounted 130

- thereon and yieldingly connected thereto, and a plurality of stops, each of which is movable into engagement with said typewheel wholly by the operator and is held 5 yieldingly either in or out of engagement with said typewheel, and means to automatically move said stops out of engagement with the said typewheel, substantially as described.
- 10 4. An oscillatory shaft and means whereby it may be oscillated, a typewheel mounted thereon and yieldingly connected thereto, a stop adapted to be moved from its normal position so as to co-act with the typewheel 15 to limit the rotation of the latter with the shaft in its forward movement and means mounted on said shaft and adapted to restore the stop to its normal position during the backward movement of the shaft.
- 20 5. An oscillatory shaft and means whereby it may be oscillated, a plurality of typewheels mounted thereon and yieldingly connected thereto, a stop for each typewheel adapted to be moved from its normal position so as to co-act with its typewheel to limit the rotation of the latter with the shaft in its forward movement, and a single means mounted on said shaft and adapted to restore all of the stops to their normal positions during the backward movement of the shaft.
- 25 6. An oscillatory shaft, and means whereby it may be oscillated, a plurality of typewheels mounted thereon and yieldingly connected thereto, a stop for each typewheel adapted to be moved from its normal position so as to co-act with its typewheel to limit the rotation of the latter with the shaft in its forward movement, and a single means adapted to restore all of the stops to their normal positions during the backward movement of the shaft, and means adapted to prevent at will the operation of the last named means.
- 30 7. An oscillatory shaft and means whereby it may be oscillated, a typewheel mounted thereon and yieldingly connected thereto, a stop adapted to be moved from its normal position so as to co-act with the typewheel to limit the rotation of the latter with the shaft in its forward movement and means adapted to restore the stop to its normal position during the backward movement of the shaft, and means adapted to prevent at will the operation of the last named means.
- 35 8. A rotatable shaft, means whereby it may be oscillated, one or more typewheels mounted on said shaft and yieldingly connected thereto, a plurality of movable stops for each typewheel, any one of which is adapted to co-act with such typewheel to prevent its rotation beyond the point determined by that stop while permitting said
- shaft to continue its movement, and means adapted to restore the said movable stop to normal position, means adapted to prevent at will the operation of the last named means, a platen, and mechanism adapted to bring the typewheels and platen into contact.
- 40 9. A rotatable shaft, means whereby it may be oscillated, one or more typewheels mounted on said shaft and yieldingly connected thereto, a plurality of movable stops for each typewheel, any one of which is adapted to co-act with such typewheel to prevent its rotation beyond the point determined by that stop while permitting said shaft to continue its movement, and means adapted to restore the said movable stops to normal position, and means adapted to prevent at will the operation of the last named means.
- 45 10. A typewheel movable from non-printing to printing position and back again, and having a projection thereon, a stop normally located out of the path of said projection and movable into said path, means movable with the typewheel and adapted to clear said stop in the movement from the non-printing to the printing positions and to strike and restore said stop to its normal position on the reverse motion of the typewheel.
- 50 11. A typewheel movable from non-printing to printing position and back again, and having a projection thereon, a stop normally located out of the path of said projection and movable into said path, means movable with the typewheel and adapted to clear said stop in the movement from the non-printing to the printing positions, and to strike and restore said stop to its normal position on the reverse motion of the typewheel, and means to prevent at will the said restoration of the stops by the last named means.
- 55 12. An oscillatory shaft, one or more typewheels rotatable thereon, and yieldingly connected therewith, said typewheels having projections thereon, a series of stops for each typewheel, normally out of the path of, but movable into the path of, the projection on such typewheel, a single means connected to the shaft and adapted to clear all of the said stops on the forward oscillation of the shaft and to strike and move all of said stops into normal position on the backward oscillation of said shaft.
- 60 13. An oscillatory shaft, one or more typewheels, rotatable thereon, and yieldingly connected therewith, said typewheels having projections thereon, a series of stops for each typewheel, normally out of the path of, but movable into the path of, the projection on such typewheel, a single means connected to the shaft and adapted to clear all of the said stops on the forward oscillation of the shaft and to strike and move all of said stops into normal position on the backward

- oscillation of said shaft, and means to prevent at will the said restoration of the stops by the last named means.
14. An oscillatory shaft, one or more typewheels mounted thereon and yieldingly connected thereto, each typewheel having a projection thereon and types disposed around a portion of its periphery, a series of stops for each typewheel, each of said stops being normally out of the path of, and movable into the path of, the projection on such typewheel, each stop in the said series being adapted, when moved into the path of the said projection, to prevent the further rotation of such typewheel with the said oscillating shaft to locate a corresponding type on the typewheel at the printing point, a single means movable with the said oscillatory shaft in the path of all of said projections and adapted to restore said typewheels to normal or non-printing position, said last named means being also movable toward and away from said stops, and mechanism to produce such motion.
15. An oscillatory shaft, one or more typewheels mounted thereon and yieldingly connected thereto, each typewheel having a projection thereon and types disposed around a portion of its periphery, a series of stops for each typewheel, each of said stops being normally out of the path of, and movable into the path of, the projection on such typewheel, each stop in the said series being adapted, when moved into the path of the said projection, to prevent the further rotation of such typewheel with the said oscillating shaft to locate a corresponding type on the typewheel at the printing point, a single means movable with the said oscillatory shaft in the path of all of said projections and adapted to restore said typewheels to a non-printing position, said last named means being also movable toward and away from said stops, mechanism to produce such motion, and means to prevent at will the operation of the last named mechanism.
16. An oscillatory shaft, means whereby it may be oscillated, one or more typewheels mounted on said shaft and yieldingly connected thereto, each typewheel having a projection thereon and a series of types disposed around a portion of its periphery, a series of stops, corresponding to the said series of types, disposed radially around each typewheel and movable into and out of the path of movement of the projection on such typewheel, and a single means connected with the said shaft and constructed and adapted to restore said stops to their normal positions out of the paths of said projections on the backward oscillation of said shaft, and to restore the said typewheels to their normal or non-printing positions.
17. A plurality of settable typewheels mounted on a shaft, stop devices carried by said wheels, a key support having openings therein, keys in the said openings and movable toward and away from the said typewheels, and normally out of engagement therewith, and means to yieldingly maintain each of said keys in position to co-act with the said stop devices.
18. A plurality of settable typewheels mounted on a shaft, stop devices carried by said wheels, a key support and having openings therein, keys in the said openings and movable toward and away from the said typewheels, and normally out of engagement therewith, means to yieldingly maintain each of said keys in position to co-act with the said stop devices, and means to move said keys out of said position to normal position.
19. A plurality of settable typewheels mounted on a shaft, stop devices carried by said wheels, a key support and having openings therein, keys in the said openings and movable toward and away from the said typewheels, means to yieldingly maintain each of said keys in position to co-act with the said stop devices, means to move said keys out of said position, and means to suspend at will the action of the last named means.
20. A plurality of typewheels, a series of keys to limit the movement of said wheels, a keyboard for said keys, comprising an inner and outer plate concentric with said typewheels and having openings therein for the said keys, a third plate between the said inner and outer plates having openings therein corresponding to the openings in the said inner and outer plates and provided with tongues extending into said openings and means connected to each key and adapted to engage the opposite sides of the said tongue to maintain the key in one of two positions, according to the side of the tongue engaged.
21. A plurality of typewheels, a series of keys to limit the movement of said wheels, a keyboard for said keys, comprising an inner and outer plate concentric with said typewheels and having openings therein for the said keys, a third plate between the said inner and outer plates having openings therein corresponding to the openings in the said inner and outer plates and provided with tongues extending into said openings and yielding means connected to each key and adapted to engage the opposite sides of the said tongue to maintain the key yieldingly in one of two positions, according to the side of the tongue engaged.
22. A plurality of settable typewheels, having stop lugs thereon, a curved keyboard adjacent to the peripheries of the typewheels, keys movable through said key-

- board and normally out of engagement with said type wheels, and means for moving said typewheels and yieldingly connected thereto.
- 5 23. In a printing device, a plurality of settable typewheels, an oscillatory shaft movable between defined limits for each printing impression, a platen movable to and from the typewheels, means connecting the said platen and the said shaft and adapted and arranged so that the said shaft moves the platen into contact with the typewheels as the said shaft nears one limit of its motion, a series of settable stops to limit the motion of the typewheels, said shaft being yieldingly connected to said typewheels, and means connected with the shaft and adapted to simultaneously return said typewheels to their normal or starting position 10 as the said shaft nears the other limit of its motion.
- 15 24. In a printing device, a plurality of settable typewheels, an oscillatory shaft movable between defined limits for each printing impression, a platen movable to and from the typewheels, means connecting the said platen and the said shaft and adapted and arranged to move the platen into contact with the typewheels as the said shaft nears one limit of its motion, a series of settable stops to limit the motion of the typewheels, said shaft being yieldingly connected to said typewheels, means connected with the shaft and adapted to simultaneously return said typewheels to their normal or starting position 20 as the said shaft nears the other limit of its motion.
- 25 24. In a printing device, a plurality of settable typewheels, an oscillatory shaft movable between defined limits for each printing impression, a platen movable to and from the typewheels, means connecting the said platen and the said shaft and adapted and arranged to move the platen into contact with the typewheels as the said shaft nears one limit of its motion, a series of settable stops to limit the motion of the typewheels, said shaft being yieldingly connected to said typewheels, means connected with the shaft and adapted to simultaneously return said typewheels to their normal or starting position 25 as the said shaft nears the other limit of its motion, and mechanism constructed and arranged to control the last named means to cause it to restore said stops to their normal or starting position as the typewheels are returned to their normal or starting positions.
- 30 25. In a printing device, a plurality of settable typewheels, an oscillatory shaft movable between defined limits for each printing impression, a platen movable to and from the typewheels, means connecting the said platen and the said shaft and adapted and arranged to move the platen into contact with the typewheels as the said shaft nears one limit of its motion, a series of settable stops to limit the motion of the typewheels, said shaft being yieldingly connected to said typewheels, means connected 35 with the shaft and adapted to simultaneously return said typewheels to their normal or starting position as the said shaft nears the other limit of its motion, mechanism constructed and arranged to control the last named means to cause it to restore said stops to their normal or starting positions as the typewheels are returned to their normal or starting positions, and means under the control of the operator to suspend the operation 40 of the said mechanism.
- 45 26. A plurality of typewheels, having the types thereon normally out of printing position, means for moving said typewheels into printing position, a series of stops to limit the motion of said typewheels, a cam bar movable concentric with said typewheels and to and from the peripheries thereof, and mechanism to move said cam bar into position to contact with said stops when moving in one direction concentric with said typewheels and out of contact with said stops when moving in the opposite direction concentric with said typewheels. 50
- 50 27. A series of settable stops movable to and from operative position, a cam bar movable to and fro across and parallel with the plane of motion of said stops, and mechanism to move the cam bar toward said stops before the beginning of the motion of said bar in one direction across the plane of motion of said stops and away from said stops before the beginning of the motion of said bar in the opposite direction across the plane of motion of said stops. 55
- 55 28. An oscillating shaft, arms attached thereto and having slots therein, a cam bar supported in said slots, cam mechanism attached to said cam bar, pins against which said cam mechanism strikes at the end of each oscillation of the said shaft, said cam mechanism being constructed and arranged to move said cam bar toward said shaft when one set of pins is struck and away from said shaft when the other set of pins is struck. 60
- 60 29. An oscillating shaft, arms attached thereto and having slots therein, a cam bar supported in said slots, cam mechanism attached to said cam bar, pins against which said cam mechanism strikes at the end of each oscillation of the said shaft, said cam mechanism being constructed and arranged to move said cam bar toward said shaft when one set of pins is struck and away from said shaft when the other set of pins is struck, and means for moving one set of said pins out of the path of the said cam mechanism. 65
- 65 30. A movable support having types thereon, a stop constructed and arranged to coact with said support to prevent its motion beyond a predetermined point represented by the stop, means yieldingly connected to the said support and adapted to move it against said stop, and mechanism operated by the said means to positively move the said support away from the said stop. 70
- 70 31. An oscillatory shaft and means whereby it may be oscillated, a type carrying member mounted thereon and yieldingly connected thereto, a stop adapted to be moved from its normal position so as to coact with the type carrying member to limit the rotation of the latter with the shaft in 75
- 75 80
- 80 85
- 85 90
- 90 95
- 95 100

- its forward movement and means mounted on said shaft and adapted to restore the stop to its normal position during the backward movement of the shaft.
- 5 32. A type carrying member movable from non-printing to printing position and back again, and having a projection thereon, a stop normally located out of the path of said projection and movable into said
- 10 path, means movable with the type carrying member and adapted to pass said stop in the movement from the non-printing to the printing positions and to strike and restore said stop to its normal position on the re-
- 15 verse motion of the type carrying member.
33. In a printing device, a plurality of settable type carrying members, an oscillatory shaft movable between defined limits for each printing impression, a platen mov-
- 20 able to and from the type carrying mem-

bers, means connecting the said platen and the said shaft and adapted and arranged so that the said shaft moves the platen into contact with the type carrying members as the said shaft nears one limit of its motion, a 25 series of settable stops to limit the motion of the type carrying members, said shaft being yieldingly connected to said type carrying members, and means connected with the shaft and adapted to simultaneously return said type carrying members to their normal or starting position as the said shaft nears the other limit of its motion.

This specification signed and witnessed this 2nd day of May 1910.
